CLAIM

The ornamental design for a telephone, as shown and described.

DESCRIPTION

FIG. 1 is a reduced-scale perspective view of a telephone showing our new design;

FIG. 2 is a front elevational view thereof;

FIG. 3 is a rear elevational view thereof;

FIG. 4 is a left side view thereof;

FIG. 5 is a right side view thereof;

FIG. 6 is a top plan view thereof;

FIG. 7 is a bottom plan view thereof; and,

FIG. 8 is another reduced-scale front elevational view thereof, showing a state in which the receiver is detached from a main body.

The broken lines in the drawings depict portions of the telephone that form no part of the claimed design.
